COMBINED GAS CANDLE AND HOLDER OR SIMILAR ARTICLE

Harold I. Gross, Beverly Hills, Calif., assignor to National Silver Company, New York, N.Y., a corporation of
New York

Filed Feb. 5, 1965, Ser. No. 83,705

Term of patent 14 years

(Cl. D48—2)

I claim:

The ornamental design for a combined gas candle and holder or similar article, as shown.
